CUPOLA INSTALLATION AND CHARGING
SYSTEM THEREFORHenry Fraser, Arbroath, Scotland, assignor to

Scotland, a corporation of Great BritainApplication November 9, 1944, Serial No. 562,725
In Great Britain September 10, 1943

3 Claims. (Cl. 266—27)

This invention relates to a cupola installation and semi-automatic charging system therefor, the cupolas being arranged singly or in a group of two or more.

For convenience, in the following description, it is assumed that the installation comprises two cupolas.

The ordinary cupola consists of a long vertical hollow cylinder having a charging door served from a charging platform or mechanical charger about mid-height of the cupola; the upper end of the cupola projects through the foundry roof, with or without a dust collecting device.

In the installation according to the invention each cupola consists of an upright cylinder merely serving to accommodate the working charge of metal and coke. The upper end of each cupola projects slightly within a dust-collecting enclosure.

The floor of the enclosure consists of a platform enclosing the tops of the cupolas, with provision for admission of air into the enclosure above the edges of the platform. The top of the enclosure merges into a smoke duct which may penetrate the foundry roof (if any), and discharge above the roof.

In operation, gases emerging from the top charge of material in each cupola pass immediately into contact with a large excess of cold air entering around the edges of the platform. The gases (if inflammable) therefore burn with a short flame and impinge directly on a baffle plate fixed above the cupola, which deflects them, and ensures that they are well mixed with cold air.

A pivoted jib crane is mounted on the platform so that the jib may swing over the tops of the two cupolas, and also over two positions on the floor where charging skips are lifted and lowered. The post of this crane is slightly inclined to the vertical so that the jib has a bias to swing from either lifting position towards its neighbouring cupola. The crane is operated by a control lever near the ground level.

Conveniently two skips are used alternately, being loaded with suitable amounts of coke, pig, scrap and flux. The skips are hung on spring balances adapted to be suspended on trolleys which travel along an overhead runway leading past coke and metal bins, to a terminus adjacent to the lifting points, the materials being weighed as they are thrown into the skips. A transfer bogie enables a skip to be carried from under the runway to either lifting point or vice versa.

In operation, the first skip is loaded and brought forward adjacent to the lifting point

where it is deposited on one end of the bogie. Meantime the empty skip has been deposited by the crane on the other end of the bogie. By shift of the bogie the first skip is now brought to the lifting point. The operator then raises the control lever which sets a winch in motion and permits a trip lever to engage a weighted operating lever, and the first skip is lifted to its upper level, when the rising sheave block actuates a jib skip lever, which releases the trip lever by means of wire ropes, and permits the weighted operating lever to drop and engage a brake, thus stopping and sustaining the skip automatically, the jib meantime being retained laterally by a jib catch. 10 The hook of each spring balance is provided with a depositing device such as a hand-operated eccentric cam or similar mechanism, whereby the loaded skip is deposited on the bogie, and the empty skip is lifted from the bogie. Meanwhile 15 the operator has moved the second skip under the runway and has lifted said skip (by operation of the depositing device) from the bogie and drawn it along the runway for loading.

At a desired moment the operator pulls a cord 20 which releases a jib catch which has been holding the jib with the first skip in the lifted position. The jib swings automatically over the cupola in use, overcoming the resistance of a counterbalance weight, and a trigger arm on the 25 skip comes into contact with a projecting arm which releases the drop bottom of the skip so that the contents fall vertically and centrally into the cupola. The skip, being now empty, is relatively light, and the counter-balance weight automatically and immediately returns the jib with the skip to the first lifted position of the skip where the jib stops and is held by the jib catch. 30 As soon as the operator is ready, he places the control lever in an intermediate position and the empty skip descends rapidly under the control 35 of the brake. Shortly before the empty skip reaches the bogie, the operator releases the control lever which falls into its lowest (or stop) position and the skip stops. The operator closes the drop bottom and lowers the skip gently on to the transfer bogie. This completes the cycle.

In the accompanying drawings Fig. 1 is a side view, Fig. 2 a front view, partly in section, Fig. 2a a detail view, drawn to a larger scale, of part 40 of Fig. 2, Fig. 3 a plan view, and Fig. 4 a fragmentary elevation, partly in section of an installation according to the invention.

In the installation illustrated each of two cupolas consists of an upright cylinder 45 merely long enough to accommodate the working charge

of metal and coke. The upper end of each cupola terminates in a substantial metal cope ring 2, and projects slightly within a dust-collecting enclosure 3 surrounding the tops of the cupolas 1, 1.

The floor of the enclosure 3 consists of a platform 4 enclosing the tops of the cupolas 1, 1. The sides of the enclosure 3 are spaced a short distance above the edges of the platform 4, thus admitting air all round the bottom of the enclosure. The top of the enclosure merges into a smoke duct 5. The horizontal cross sectional areas of the enclosure 3 and of the cupolas 1, 1, are preferably in the ratio of at least 7:1. The cross sectional areas of the smoke duct 5 and of the cupolas 1, 1, are preferably in the ratio of about 2:1. The height of the enclosure 3 is a multiple of the diameter of the largest cupola if the cupolas are of unequal diameters.

A sliding door (or doors), as 6, forming at least part of one side of the enclosure is (or are), arranged to permit the passage of the jib of a crane with skip hereinafter described.

In operation, gases emerging from the top charge of material in each cupola pass immediately into contact with a large excess of cold air 25 entering around the edges of the platform 4. The gases (if inflammable) therefore burn with a short flame and impinge directly on a baffle plate 7 fixed above each cupola, which deflects them, and ensures that they are well mixed with cold air. Thus, the velocity and temperature of the gases emerging from the cupolas into the relatively spacious enclosure 3 fall rapidly and there is no need to line the enclosure 3 and smoke duct 5 with firebrick. Wire-resisting plaster is sufficient. The overhead structure (consisting of the platform 4, enclosure 3, and duct 5) may be relatively light.

Nearly all the dust is deposited at once on the platform 4, where it causes no inconvenience, and may be removed by any convenient means. Owing to the indraft of cold air around the edges of the platform little grit fall off the platform 4. Very little grit is carried up to the duct 5.

A pivoted jib crane is placed so that the jib 8 may swing over the tops of the two cupolas for temporary arrest by stops, and also over two stations at the ground level, where charging skips are lifted and lowered. The post 9 of this crane is slightly inclined to the vertical, so that the jib 8 has a bias to swing from either lifting position towards its neighbouring cupola and stop 29. The crane is operated by a control lever 10 near the ground level through the intermediary of a winch 17. There is no charging platform, and there are no operatives except those loading the skips 11. Lifting and lowering positions are at the same station, the position used being always that nearest the cupola in use. During melting, the door 6 adjacent to the cupola being operated is kept open.

Conveniently two skips 11 are used alternately, these being loaded at a loading station with suitable amounts of coke, pig, scrap and flux. An overhead runway 12 extends from the loading station transversely of rails 13 on which is movable a transfer bogie 14 capable of receiving two skips. The skips are hung on spring balances 15 suspended on trolleys 16 which travel along the runway 12.

In operation, the first skip 11 is loaded and brought forward adjacent to the lifting point where it is deposited on one end of the bogie 14. Meantime the empty skip has been deposited by

the crane on the other end of the bogie 14. By shift of the bogie 14 the first skip is now brought to the lifting point. The operator then raises the control lever 10 to actuate a weighted lever 19 having an arm 19a operatively connected to the movable element of a double-ended friction clutch 17a the shaft of which is geared to the winch 17, whereby to place said clutch in driving position to set the winch in motion. A spring influenced trip lever 18 engages a catch 19b on the weighted lever 19 whereby temporarily to retain said lever in raised position. The first skip is then lifted to upper level, when the sheave block 20 actuates the jib trip lever 21 operatively connected to a further skip trip lever 21a, whereby to cause the trip lever 21a to trip a jib catch 24 connected by a wire rope 22 to the spring-influenced trip lever 18, thereby actuating the trip lever 18 to release the weighted lever 19. The weighted lever 19, returning to initial position by gravity, disengages the driving element of the clutch 17a and engages the braking element whereby the skip 11 is stopped and sustained automatically, the jib 8 being retained laterally by the jib catch 24, see Fig. 1.

The jib is retained against the catch 24 under the influence of a counter-balance weight 28 suspended on a wire rope 28' passing over a guide pulley 28'' and connected to the nose of the jib 8.

The hook of each spring balance 15 is provided with a depositing device including a hand-operated eccentric 15' whereby the loaded skip is deposited on the bogie 14, and the empty skip is lifted from the bogie. Meanwhile the operator has moved the second skip under the runway 12 and has lifted said skip (by operation of the respective depositing device) from the bogie 14, and drawn it along the runway 12 for loading.

At a desired moment the operator pulls a cord 26 which releases the jib catch 24 which has been holding the jib 8 with the first skip in the lifted position. The jib swings automatically over the cupola in use, overcoming the resistance of a counterbalance weight 28, and a trigger arm 27 on the skip comes into contact with a stop or projecting arm 29, releasing the drop bottom of the skip, so that the contents fall vertically and centrally into the respective cupola, see Fig. 4. The stop 29 is hingedly connected to the frame of the cupola and may be turned up out of the path of movement of the skip when not required, as shown in dotted lines in Fig. 4. There is a stop or hinged projecting arm 29 for each cupola. The skip, being now empty, is relatively light, and the counter-balance weight 28 automatically and immediately returns the jib with the skip to the first lifted position of the skip where the jib stops and is held by the jib catch 24. As soon as the operator is ready, he places the control lever 10 in an intermediate position and the empty skip descends rapidly under the control of the brake. Shortly before the empty skip reaches the bogie 14, the operator releases the lever 10 which falls into its lowest (or stop) position and the empty skip stops. The operator closes the drop bottom and lowers the skip gently on to the transfer bogie 14. This completes the cycle.

The winch 17 is driven by an enclosed dust-proof motor 30 supported on a lifting unit platform 31 placed at any convenient position adjacent to the cupolas. A winding drum 32 actuated by the winch operates a wire rope 33 leading to the jib of the crane and from this rope 33 the skip is suspended while lifting and lowering. The winch 17 contains a double ended friction clutch 17a controlled by one lever. The "up"

position of the lever 10 is "lift" and the "down" position is "stop," while the intermediate or "free" position is "lower." The lowering function is gravity-operated by the weight of the skip, and is controlled by the brake to prevent excessive variation in speed whether of an empty or a full skip.

While the installation described uses one loading runway for two hoisting positions with two skips, the installation might comprise a circular runway in which the skips do not have to pass each other, and a different kind of transfer bogie, or even no bogie at all, may be found convenient.

What is claimed is:

1. A cupola loading installation comprising a 15 dust-collecting enclosure having a floor through which projects the upper end of the cupola, said floor constituting a platform, said enclosure con-

trived for entrance of air above said platform, a smoke duct into which merges the top of said enclosure, a jib crane supported on said platform and controllable from the ground level, a jib catch and a stop spaced from one another, said crane being operable to lift and lower charging skips and to swing relatively to the cupola between said jib catch and said stop.

2. An installation as claimed in claim 1 including a projecting arm adapted to release the drop bottom of a skip when in cupola-charging position.

3. An installation as claimed in claim 1 in which a counterbalance weight connected by a rope to the jib opposes the movement of the jib in its swinging movement towards the cupola.
